UNITED STATES PATENT OFFICE

2,542,400

INFANT'S ANCHORED DISH

John M. Donofrio, Toledo, Ohio, assignor to
Dismat Corporation, Toledo, Ohio, a corpora-
tion of Ohio

Application March 26, 1948, Serial No. 17,197

3 Claims. (Cl. 65—15)

1

This invention relates to anchoring of vessels, carriers and containers, especially against shifting as to a normal support region therefor, thru the medium of concealed means more readily responsive to attachment than detachment.

This invention has utility when incorporated in dishes, more particularly as to food containers to be placed on trays for infants. There is adjustable placing of the dish at a location where the child may reach it for access to the food therein. However, it is primarily in order that the parent or nurse, in this act of placing the dish, shall do so by relying more than on the mere contents of the dish and the weight of the dish. That is, the dish is given a slight thrust flatwise as to its under face or side, at least to have its drop rim closely approach, if not actually contact the upper side of the tray. Inward from such rim, and having an at-ease planar extension slightly below the plane of the rim's lower free edge, is yieldable suction cup means. The thrust pressure in firmly depositing the dish before the child, distorts or spreads the suction cup rim to effect firm anchorage and by means away from tampering exposure to the child.

This invention may also be used for anchoring cuspidors, dog dishes and the like, to the floor or their supporting surfaces.

Referring to the drawings:

Fig. 1 is a plan view of an embodiment of the invention in a food dish for infants;

Fig. 2 is a side elevation of the dish of Fig. 1, a portion being broken away in proximity to a suction cup therefor;

Fig. 3 is an enlarged sectional fragment of the dish with a suction cup therefor partly in section; and

Fig. 4 is a fragmentary detail of the dish and a suction cup therefor in gripping relation as to a supporting face, such as the top of a tray for an infant's high chair.

An infant's food dish 1 is herein shown as of a circular form having a food-carrying bottom 2 bounded by a riser wall 3 extending to a top 4 from which there is herein shown a slightly outwardly flaring depending rim 5 with a free endless edge 6. The rim edge 6, desirably lies in a plane to some extent lower than underside 7 of the dish bottom 2.

Under the invention herein disclosed, a location is provided for the special anchoring means, in this instance shown as in multiple. In the event the dish 1 be molded, as of plastic, there may be an approximately uniform wall thickness throughout, thereby leaving a re-entrant space or channel

2

8 open at the lower side and between the rim 5 and the riser wall 3. There is shown uniformly spaced about in the groove or channel 8, wall thickened regions, columns or lugs 9 in which may be screw portions 10 of suction cups having base or collar portions 11 with flat upper side 12 snugly seating against flat complementary lower side 13 of the lug 9.

From the suction cup base portion 11, say of 10 yieldable rubber-like material, and integral therewith is a spread or flare portion having a convex outer face or zone 14 with an inner concave polar zone face 15. Remote from the base 11, the faces 14, 15, terminate in a circular planar 15 yieldable ring face 16. The face 16 is, at normal or uncompressed position for the device, in a flat relation parallel to the faces 12, 13. Under the invention, the concave face 15 defines an open bottom cup or chamber 17 of extent fractionally 20 below the plane of the edge 6. When the vessel or dish 1 is thrust downwardly to anchor it by means of the suction cups, the faces 14 and 15 of the cups are distorted and spread, reducing the capacity of the cup 17 and changing it into the form 25 18 as shown in Fig. 4, wherein also the face 16 is tilted as at 19 to the surface 20, of a tray or the like, to which the cups adhere.

What is claimed and it is desired to secure by Letters Patent is:

1. A dish to be held having a bottom lying in a first plane, there being integral with said bottom a riser wall rising to a top, surrounding said bottom a depending endless rim connected to said top but spaced from said riser wall and therebetween forming a channel, said rim having a free lower edge in a second plane spaced more remotely from said top than said first plane, there being a plurality of thickened portions forming columns in said channel integral with a wall of said channel and providing seats at the lower end of said columns, and suction cups attached to said columns having surfaces seated against said seats, said suction cups lying within the periphery of said depending rim and being substantially concealed by said rim.

2. A vessel to be anchored to a flat support, said vessel having a bottom lying in a first plane, there being integral with said bottom a riser wall rising to a top with a dependent rim spaced from said riser wall to form an endless channel with said rim having a free lower edge extending downwardly to a second plane spaced more remotely from said top than said first plane, there being a plurality of seat-providing lugs in said channel integral with said riser wall, and suction

cups having complementary seats assembled against said lug seats, said suction cups lying within the periphery of said depending rim and being substantially concealed by said rim.

3. An infant's dish to be anchored to a table top, said dish having a planar bottom bounded by a downwardly open channel integral therewith formed by a riser wall rising to a top and thence downwardly extending into a skirt having a free edge lower rim in a plane spaced downwardly from said planar bottom, there being seat-providing lugs integral with said channel, and suction cups having complementary seats assembled against said lug seats, said suction cups lying within the periphery of said skirt rim and being substantially concealed by said skirt.

JOHN M. DONOFRIO.
